UNITED STATES PATENT OFFICE.

WILLIAM P. BETTENDORF, OF DAVENPORT, IOWA.

DESIGN FOR A BRAKE-BEAM FOR CARS.

SPECIFICATION forming part of Design No. 26,489, dated January 5, 1897.

Application filed June 29, 1896. Serial No. 597,478. Term of patent 14 years.

To all whom it may concern:

Be it known that I, WILLIAM P. BETTENDORF, a citizen of the United States, residing at Davenport, in the county of Scott and State 5 of Iowa, have invented and produced a new and original Design for Brake-Beams for Cars, of which the following is a specification, reference being had to the accompanying drawings, in which—

- 10 Figure 1 is a plan view of a brake-beam embodying my improved design. Fig. 2 is a transverse sectional view of the same taken on dotted line 2 2, Fig. 1.

These plates A are so shaped that when 15 united together they form into one integral whole the end supports for the brake-shoe heads, the finger-guards, and contours for the body of the beam, which correspond substantially to the lines of a truss, so as to embody the principle of the same. The forward 20 edge of the beam is most advanced at its center of length, and recedes from this most-advanced point at a suitable angle on both sides of the same to near the base of the finger- 25 guards B, where they are curved upward toward and merge into the forward ends of said finger-guards. The peculiar feature of this forward edge of the brake-beam is that the edge portions of the two plates A are during 30 their process of formation given a longitudinal semicircular bend b, so that when said plates are united they form a tube which extends the entire length of the brake-beam, from the forward end of one finger-guard to 35 that of the other. Nearer the rear edge of the plates A they are each provided with longitudinal semicircular and outwardly-curved ribs C, which are made by the dies of a press in which they are formed with their inner 40 surfaces possessing the reverse curvature thereof, so that when said plates A are united

together a substantially longitudinal tube is formed, which traverses the entire length of the brake-beam and has its ends extended beyond the outer sides of the finger-guards a 45 sufficient distance to provide adequate support for the brake-shoe head. The finger-guards are made tubular by rolling or curving the outermost marginal portion of the part of plates A, devoted to that construction, 50 so that when the said plates A are united together the tubular form results therefrom. At the base of the finger-guards these tubular portions thereof spread and merge into the longitudinal tube C, and on the opposite 55 side of the said tube C, and in alinement with the finger-guard tube, is a continuation of the latter.

At about the center of length of the brake-beam, between the tube C and the tubular 60 forward edge of the same, said beam is provided with an oblong opening the edges of which are tubular, and between this opening and the forward tubular edge of the beam it is provided with a tubular-shaped bearing 65 which is substantially at right angles to the tube C, and forms a continuation or companion bearing for said tubular bearing and is located between said tube C and the rear edge of the brake-beam. 70

The rear edge of the brake-beam as well as the tube C, which is substantially parallel with said rear edge, may be at right angles to the line of travel of the car to which the beam is applied. 75

What I claim is—

The design for a brake-beam for cars as herein shown and described.

WILLIAM P. BETTENDORF.
